(57) **CLAIM**

The ornamental design for a ceiling fan blade, as shown and described.

DESCRIPTION

FIG. 1 is a perspective view of a ceiling fan blade in accordance with my design;

FIG. 2 is a top plan view of the ceiling fan blade in accordance with my design;

FIG. 3 is a bottom plan view of the ceiling fan blade in accordance with my design;

FIG. 4 is a left-side elevation view of the ceiling fan blade in accordance with my design;

FIG. 5 is a right-side elevation view of the ceiling fan blade in accordance with my design; and,

FIG. 6 is a front elevation view of the ceiling fan blade in accordance with my design.

The broken line disclosure of elements is understood to represent portions of the article in which the design is embodied and are environmental, but form no part of the claimed design. The fan blade in FIGS. 2-5 have been broken-away from the ceiling fan housing for ease of illustration.

1 Claim, 2 Drawing Sheets
